his ATTORNEY

UNITED STATES PATENT OFFICE.

RUDOLF KEHR, OF WEEHAWKEN, NEW JERSEY.

DESIGN FOR A TRIMMING FOR FABRICS AND LIKE MATERIALS.

59,010.

Specification for Design.

Patented Sept. 13, 1921.

Application filed April 21, 1921. Serial No. 463,405. Term of patent 3½ years.

To all whom it may concern:

Be it known that I, RUDOLF KEHR, a citizen of the United States, residing in the town of Weehawken, county of Hudson, and State of New Jersey, have invented a new, original, and ornamental Design for Trim-
mings for Fabrics and like Materials, of which the following is a specification, refer-
ence being had to the accompanying draw-
ing, forming a part thereof.

The figure is a plan view of a portion of a fabric to which my trimming is applied.

I claim:—

The ornamental design for trimming for fabrics and like materials, as shown.

RUDOLF KEHR.
